UNITED STATES PATENT OFFICE

JOSEPH A. V. TURCK, OF WILMETTE, ILLINOIS, ASSIGNOR TO FELT & TARRANT MFG. COMPANY, OF CHICAGO, ILLINOIS, A CORPORATION OF ILLINOIS

CALCULATING MACHINE

Application filed July 7, 1928, Serial No. 573,431. Renewed February 18, 1932.

This invention relates to a multiple order keyboard calculating machine, which will perform automatically the process of multiplication and other calculations involving any suitable character of multiple strokes or actuations of an adding mechanism and repetitions of the same number, taken either positively or negatively, by a purely mechanical operation according to the denominations of the multiplicand and multiplier, or according to the other elements of the problem, without the necessity for progressive and separate settings of the parts during the performance of the operation.

The essential object of the invention is to provide a calculating machine such as above set forth having a motor drive mechanism for effecting the operation of the machine to perform the problem, the power of the motor drive mechanism being connectable for the purpose of actuating the machine, on setting of both factors of the problem and being automatically disconnected from the mechanism of the machine on the solution of the problem. In accordance with a further feature of the invention, the motor drive mechanism is combined with a hand drive for effecting the multiple-stroke operation of the machine and provision is made whereby the machine may be optionally driven by hand or by the motor drive mechanism.

In addition to the general objects recited above, the invention has for further objects such other improvements in construction and advantages in operation as may be found to obtain in the mechanism herein-after described or claimed.

In the accompanying drawings, forming a part of this specification and showing, for purposes of exemplification, a preferred form and manner in which the invention may be embodied and practiced, but without limiting the claimed invention to such illustrative instance or instances:

Figure 1 is a side elevational view of a calculating machine constructed in accordance with the improvements of the invention and showing the machine supported in

a frame containing a motor and drive gearing parts;

Fig. 2 is a longitudinal sectional elevational view of the calculating machine looking toward the left, on II-II of Fig. 13;

Fig. 3 is another longitudinal sectional elevational view of the machine taken on its left hand side, on the line III-III of Fig. 15, and looking toward the right;

Fig. 4 is another longitudinal vertical sectional view of the machine, on the line IV-IV of Fig. 15, looking toward the right;

Fig. 5 is an enlarged vertical sectional view taken at the right hand side of the machine, on the line V-V of Fig. 13, and looking toward the right (the multiple-control key-plate being omitted);

Fig. 6 is another enlarged longitudinal sectional view looking toward the right and taken on the same plane but further to the front than that of Fig. 5 (omitting some of the mechanism at the rear, which is shown in Fig. 5);

Fig. 7 is another longitudinal sectional elevational view of the machine taken at the extreme right hand side just within the case and looking toward the left, the side casing being removed;

Fig. 8 is another longitudinal sectional view of the machine taken at the right hand side and looking toward the left but in a plane, on the line VIII-VIII of Fig. 13, further to the left than that of Fig. 7.

Fig. 9 is a fragmentary longitudinal sectional view looking toward the right and taken in a plane somewhat further to the right than that of Fig. 6;

Fig. 10 is a fragmentary sectional view taken transversely of the machine in planes 90 indicated by the line 10-10 of Fig. 9;

Fig. 11 is a detailed side elevational view of the motor and hand drive control device;

Fig. 12 is a detailed vertical sectional view of parts shown in Fig. 11;

Fig. 13 is a partial plan view of the calculating machine;

Fig. 14 is a partial plan view of a calculating machine with the top cover plate removed and showing the drive and con-

trol parts at the right hand side of the machine; and

Fig. 15 is a plan view of the machine to the left of the partial plan view shown in Fig. 13.

The same characters of reference designate the same parts in each of the several views of the drawings.

In its present embodiment, the invention is incorporated in a calculating machine of the multiple order key driven type, such as the well known "Duplex comptometer" the general character of which is exemplified in the prior Letters Patent of the United States to Dorr E. Felt Nos. 762,520 and 762,521 dated June 14, 1904, No. 960,528, dated June 7, 1910, No. 996,009, dated June 20, 1911, and No. 1,003,723 dated September 19, 1911. Moreover, the invention is particularly adapted and in the present instance especially designed for employment in connection with the invention shown, described and claimed in my prior Letters Patent of the United States No. 1,316,523, dated September 16, 1919, which invention involves broadly the automatic performance of the operation of multiplication in which both factors are multiple-place and completely predetermined, and effects the entire operation with mechanism of which the ordinal positions are permanent, said mechanism remaining and operating in fixed ordinal places in the machine. Inasmuch as the details of construction of the comptometer may be readily understood from the prior Letters Patent hereinabove referred to and of the multiplying mechanism from my said prior Letters Patent, a condensed description of the general features of construction and operation of the comptometer mechanism and the multiplying mechanism with its various controls and other parts, will be ample for an understanding of this invention.

46 The various instrumentalities of the calculating machine are supported by the vertical longitudinal plates 1, constituting a part of the frame of a machine which is closed at the top by the cover plate 9. The frame preferably comprises the vertical side or retaining plates, such as shown at 1, and similar intermediate or division plates, arranged respectively in the spaces between the numeral wheels 2. All of these vertical plates are rigidly connected by suitable cross bars or tie rods 3 to form the main frame.

The adding or accumulating mechanism (see especially Figs. 2, 3 and 4)

60 The accumulating mechanism, which includes the numeral wheels is actuated, in the calculating operation, by ordinal sets of keys 4 extending vertically through the top plate 9. The lower end of each key stem

is pressed upward by a lever 5 and a spring 6 carried by lower frame parts 7. Each column or set of keys 4 forms a part of the accumulator mechanism for transmitting to its numeral wheel an amount of travel proportionate with the particular key operated and the accumulator mechanism for each column of keys and its corresponding numeral wheel includes a column actuator 8 pivotally mounted on a cross rod 51 on the frame 1 and yieldingly held up by an accumulator actuating spring 10. Each key is provided with a stem extending down and bearing upon a column actuator, and the key at the extreme front of the machine being farther from the pivotal axis of the column actuator than the key at the extreme rear of the machine moves the column actuator through a lesser arc than does the key last mentioned. It will be understood that the keys of each column are numbered from "1" to "9" in front to rear order of the machine and that the key at the extreme front is adapted to effect actuation of the column actuator through an arc approximately 1/9 of that produced by the operation of the key at the extreme rear of the machine and that, upon depression of intermediate keys, the column actuator is moved through arcs proportionate with the value of the intermediate key actuated.

The column actuator 8 of each order or column of nine keys of the machine is adapted to impart calculating movement to an accumulator and for this purpose is provided at its forward end with a rack which meshes with an accumulator pinion 18 journaled upon a transverse shaft 19 that extends across the machine. The pinion 18 of each order forms a part of an internal ratchet mechanism, not herein illustrated in detail, but disclosed in the prior patents hereinabove mentioned, and which becomes effective upon the upstroke of the column actuator to clutch the pinion 18 to a lantern wheel 21 and a transmitting pinion or gear 26 that rotates with the lantern wheel and is adapted to mesh with an intermediate gear 24 on the transverse shaft 25. The gear 24 in turn meshes with the numeral wheel pinion 27 which drives the numeral wheel 2 of the accumulator mechanism. It will be understood that each time the column actuator is depressed the ratchet mechanism 20 moves idly and hence no motion is transmitted to the gear train ending with the numeral wheel 2; however, upon the return or upward movement of the column actuator, by the well understood spring action, the transmitting pinion 26 is clutched to the accumulator pinion 18 and the gear train rotates the numeral wheel 2 through the arc determined by the particular key actuated.

Carrying mechanism is provided in each

accumulator mechanism for the purpose of actuating the accumulator of the next highest order of the machine each time a carry is to go over from a lower order, for instance, when 10 is accumulated on the wheel of a lower order. For present purposes, it will not be necessary to give a detailed explanation of the carrying mechanism and a brief reference to parts of the carrying mechanism together with a general statement of their function, will suffice, because ample description of the same will be found in the prior patents above mentioned. The carrying mechanism in each order is of the standard "Duplex comptometer" type having provision for permitting ordinal keys to be depressed simultaneously and column actuator impulses delivered in two or more adjacent orders, and yet for preventing any carrying impulses released from a lower one of said orders from being actually delivered to the next higher of said orders until the column actuator movement of such higher order is completed. This operation of effecting simultaneous key driven actuation of a plurality of common actuators in adjacent orders, the strokes overlapping each other in any manner, is the action that has been referred to as "Duplexing". Attached to the accumulator gears are carrying pinions 18' which respectively mesh with and drive carrying gears (see Patent No. 1,816,528) the latter functioning for the purpose of winding the carrying motor springs which connect the carrying gears yieldably with rotary escapements having two armed carrying cams. The said escapements are given, by means of the said carrying motor springs, a half revolution at each half revolution of the carrying gears or whole revolution of the carrying pinions for the purpose of actuating the carrying levers 32 each of which is pivoted on the cross pivot shaft or rod 33 and is arranged in line with the lantern wheel in the next higher order of accumulator mechanism, said carrying levers being raised by the carrying cams on each half revolution of the latter and having means operating on the pins of the said next higher lantern wheel to move the latter and other parts of its accumulator mechanism one step at each carry. In order to prevent the carrying escapement member from effecting a carrying throw of the co-operating carrying lever at a time when the accumulator of the higher order is already in motion or is about to be moved by the column actuator that has been or is being depressed by one of the keys in that higher order, there is provided a carry detaining latch 35 in each order which operates to block the carrying escapement member, whenever the column actuator of the higher order has been or is being depressed by one of the keys in that order and thus delays the

carry from the lower to the higher order until the column actuator regains its normal elevated position.

Such is, in brief outline, the manner in which prime actuations and carrying impulses are imparted to the accumulator mechanism in the Duplex comptometer of the above mentioned patents. It will be understood that these actuating mechanisms are associated with various stop mechanisms set forth in the said patents, to limit the movements imparted to the accumulator mechanisms by the prime actuations and carrying impulses; all of these stop mechanisms are shifted into and out of their various stop positions to impose additional restriction on the movements of the carrying devices and to the prime actuations of the accumulators.

The cancelling or zeroing operation (see especially Figs. 7 and 8)

The cancelling means whereby the numeral wheels are reset at zero comprises a cancelling actuator, or zeroizing controlling means, consisting in this instance of a cross rock shaft 52, crank handle 53 and slotted cam device 54. These parts operate on a cancelling device comprising a segment lever 55 actuated by the slotted cam 54 (Fig. 7), a cancelling pinion 56 on the cancelling or intermediate shaft 25, and means by which said shaft may rotate the intermediate gears 24 when the shaft is in a certain position relative to the gears. The cancelling means also comprises devices effecting a one-space adding movement of the column actuators, consisting of a transverse bar 57 (Fig. 3) adapted to depress the column actuators one space and give a one space adding movement to the accumulator mechanism, which bar is reciprocated vertically (Figs. 3 and 7) by the roll mounted on slotted cam 54 (Fig. 7) through the medium of arms 58, which carry the bar at their ends and are pivoted at 59 to the frame 1 (as more fully shown and described in the aforesaid Felt and Turck Patent 1,072,934).

For accuracy in bringing the numeral wheels from their various positions to the "0" position, those of the second higher orders are first brought to the "8" position, and the units wheel is brought to the "9" position; then the cross bar 57 and the column actuators having been depressed one step, rise and move all of the wheels one step. The wheels of higher order than units move to the "9" position and the units wheel immediately thereafter moves to the "0" position, the said movement of the units wheel being detained in a known manner by a slightly elongated tooth 61 on its cancelling stop 37 (Fig. 3), with the result that the carrying mechanism operates, successively but practically instantaneously, across

the machine from right to left to bring the said wheels of higher order to the "0" position and complete the cancelling operation. The above mentioned cancelling clearing or 5 zeroizing mechanism is more particularly described in the prior Letters Patent of the United States of Dorr E. Felt and Joseph A. V. Turck, No. 1,072,934.

With the said accumulating or adding 10 mechanism or with other accumulating mechanisms suitable for the purpose, there is combined a multiple stroke mechanism as hereinafter described. The said accumulating mechanism may be said to represent 15 potentially one of the numbers or factors which are to be multiplied together, though such factors may not appear at that time on the numeral wheels of the accumulator mechanism. The multiple stroke mechanism 20 is set to control potentially the other factor or multiplier of the product to be obtained, and is connected with the said accumulator mechanism in such manner that, when operated, it will repeat each order of 25 the accumulator mechanism, representing a denomination of the multiplicand, a number of times, according to the denominations of the multiplier, so as to accumulate the sum of the products of the multiplicand by 30 each denomination of a multiplier. Thus the additive length or degree of stroke may represent the multiplicand and the number of strokes represent the multiplier.

For example, suppose that 456 is to be 35 multiplied by 123: the machine is adjusted for multiplication by connecting the actuating means of the accumulator mechanism, in the various orders thereon, with the corresponding orders of the multiplying mechanism. The multiplicand is set on the accumulating mechanism by depressing the 4, 5 and 6 keys. This setting will be in the tens of thousands (5th order), thousands (4th order), and hundreds (3rd order) columns, 45 according to the number of places in the multiplier, so that the product may be accommodated on the numeral wheels with the units of the product in the units order. In effect, such setting is part of the multiplication process and has multiplied 456 by 100, and the first actuation of the numeral wheels when their column actuators are released by the multiplying mechanism will show 50 45,600. The construction of the multiplying mechanism is such that the depression of the set keys in the orders named will set the corresponding orders of multiplying mechanism so that, when actuated, its fifth order will stop the corresponding accumulator 55 numeral wheel at 4, its fourth order will stop its wheel at 5 and its third order will stop its wheel at 6; each cycle of the multiplying mechanism while its connection with the accumulator mechanism are as above 60 stated would add 4, 5 and 6 on the said

numeral wheels of the 5th, 4th and 3rd orders, respectively, amounting to an accumulation of 45,600 at each cycle of movement. In the example given the multiplier 70 being 1 only one such cycle is required.

Before the multiplying mechanism is thus actuated controls for its various orders are set, so that three of its orders (representing 123 in the case supposed) may successively have first one cycle of movement, next two cycles of movement, and then three cycles of movement. The said controls also cause the connections between the respective orders of multiplying mechanism and accumulator mechanism to shift or trans-set successively and automatically to the right; so that, in the one 1-cycle movement, the operative connection of the multiplying mechanism with the 5, 4 and 3 orders of the adding mechanism will be released, and the 4th, 3rd and 2nd orders will become connected, each respectively with the same additive degree of movement which the 5th, 4th and 3rd orders formerly had, so that now the digits 456 will be actuated at each stroke in this new setting. This setting continues during the two cycle movement; after the two cycle movement has been completed the set connections will again be trans-set each one place to the right, the 4th, 3rd and 2nd orders becoming disconnected and the 3rd, 2nd and 1st becoming connected, and so remaining during the three cycle movement. This shifting of connection under the set controls is such that the highest connected multiplying lever will continue to add 4 at each cycle of movement, in whichever column or order of accumulator mechanism it is acting; the next higher lever will continue to add 5 and the lower lever will continue to add 6. The additive degree of movement to add 4, which the highest multiplying lever originally has is thus preserved, but trans-set to the right from lever to lever until the requirements of the example have been fulfilled. The same is true of the other multiplying levers which have been set. During such successive accumulations or additions the accumulator mechanism acts in a known manner, carrying from wheel to wheel or right to left. The result is a showing of 56088 on the numeral wheels. The process is a mechanical and automatic repetition of additions in the ordinary process of multiplication when worked from left to right, beginning with the ten thousands and ending with the units. Thus, the first 1-cycle movement accumulates 45600; the second 2-cycle movement accumulates 9120; and the 3-cycle movement accumulates 1368 more, the total being the correct product and shown on the numeral wheels.

In the above operation, the principal functions to be performed automatically are to 130

control the multiplying levers so that they will make actually the required number of strokes in all the denominations of each setting, to trans-set the additive degree of movement of each lever to the next lower lever at the end of each cycle of movement, and to prevent any accumulation of the numeral wheels of the adding mechanism during the period of trans-setting. However, in order to preserve the continuity of the setting of the multiplier, there must be operations of the control mechanism, for any intermediate ciphers which it contains must be trans-set and the multiplicand must be trans-set past such cipher. For this purpose, the multiplying lever makes a stroke, but such stroke representing a cipher must not actuate the adding mechanism. This is preferably accomplished by giving eleven steps or positions to the multiple control mechanism, represented on its indicators by 9, 8, 7, 6, 5, 4, 3, 2, 1, 0 and a blank. If an indicator 219 be set at 9, any set multiplying lever will give nine strokes, and this capacity may then be trans-set to the next lower lever. So of all the other digits, according to their value. The trans-setting of all the levers occur simultaneously after the stroke from 1 to 0 and after said stroke the adding mechanism is disconnected, by the cipher control mechanism. For example, in multiplying 456 by 1002, the 456 is caused to appear once on the adding numeral wheels in such position as to represent 456000. The three multiplying levers set to give 456 are now trans-set three places to the right, without actuating the adding mechanism. And then they will cause its actuation twice for a total value of 912. The multiple control indicators, with which the mechanism functionally corresponds, successively show during the strokes of this operation (the blank spaces of the indicators being represented by dashes, and it being understood that all indicators which are not set show blank spaces):

104	1 0 0 2
	0 0 0 2
	- 0 0 2
	- - 0 2
	- - - 2
	- - - 1
	- - - 0
	- - - -

105 The product 456912 appears on the adding numeral wheels at the end of the strokes to - - - 0, and during the last stroke to - - - -, the whole machine resets itself in normal position.

110 In the adding mechanism, all ciphers are in the usual manner, represented by unset keys. The corresponding multiplying levers remain set at normal, or what may be called neutral position and have no additive movement. But this neutral setting is trans-set

as are all digits, so as to preserve the continuity of the multiplicand. The important feature is the automatic taking care of intermediate ciphers in the multiplier, so that the continuity of both factors is preserved, and that of the multiplicand in any trans-setting, and the operation of the machine as a whole is continuous without inaccurate accumulation.

115 *The multiple stroke mechanism (see especially Figs. 5, 2, 4 and 3)*

120 Arranged substantially in line with each order of adding mechanism is a multiplying lever having the function, when connected with its corresponding column actuator 8 and oscillated in vertical longitudinal planes by a main rock shaft 100 of depressing the column actuator for a greater or less distance, according to the setting of the lever and thereby causing an accumulation on the adding mechanism as the column actuator rises to normal position. Each multiplying lever consists of two independent but connectable parts pivoted on a cross rod 101 125 of the frame. One of these parts, which for convenience is termed the rack lever, has a rearward arm 102 formed with an inner toothed rack 103 by which it may be locked in any of ten different positions to its companion lever part, with an outer toothed rack 104 by which it may be temporarily locked to a lever part in the next higher order, with a tooth 105 by which a cross stop bar 106 of the frame arrests it in normal position and with a ratchet 107 by which it may be held when set by an adding machine key at any one of nine distances from the bar 106 so as to be capable of accumulating in its order any multiplicand digit from 1 to 9 in a stroke, the number of strokes representing the multiplier. The said racks and ratchets are formed on arcs concentric with the lever pivot, and their teeth are related to the nine keys of the order of the adding machine. The lowest ratchet tooth is related to the one key and ninth tooth of the 9 key, and the lowest rack notches are related to the 1 and the ninth (inner and outer) rack notch is related to the 9 key. 130 The other lever part, which is termed the dog lever, is composed of two rearwardly extending arms 108 between which a locking dog 109 (Fig. 5) is slidable radially (shown and described in my aforesaid Patent 1,316, 135 523, in its Figs 22 to 30 and at its page 9, lines 12-68 et seq.). Mounted on the dog lever is a roller 110, and the roller of each dog lever is operable from below by a cam 111 fixed on the main rock shaft 100. Springs 112 and 113 pull the lever parts rearwardly and downwardly, thereby tending to seat the tooth 105 against the bar 106, to elevate the forward lever arm 114 140 and to hold the rollers 110 against their

respective cams. Each arm 114 is provided with a lateral lug 115 by means of which the multiplying lever is adapted to be connected with its companion column actuator. For 5 each ratchet 107, there is provided a pawl 116 pivoted to the frame at 117, formed with a tail 119, and pressed toward the ratchet by a spring 118. A transverse rock bar 120 provided with projections 121 is 10 adapted to depress the tails 119 of the pawls 116 and to release all of the pawls from their respective ratchets, after the desired rack levers have been set for operation.

The normal position of the cams 111 is 15 at the top or extreme of their throw, supporting the rollers 110 and dog levers in their most elevated position. Assuming that the rack levers have been connected with their column actuators, as later explained, 20 and that 456 is to be multiplied: the 4, 5 and 6 keys of the adding machine are depressed, in successive orders, to the left of the units column according to the number of places in the multiplier. This, through column actuator 8 and link 139, elevates the rear arms 25 of the corresponding rack levers 102, which were resting with their teeth 105 on the cross stop bar 106 and were held down by their springs 113, with the result that said levers 30 are held up by the pawls 116, which engage respectively the fourth, fifth and sixth notches of the ratchets 107 of the respective levers. While in these positions, the said 35 rack levers are connected each to its companion dog lever by the dogs 109. Each dog 109 slides in slots 122 in the dog lever, being held in place by a sliding retaining frame (see Figs. 52 to 54 inclusive of Patent No. 1,316,523) and is pressed outwardly by a 40 spring. Each dog has a left hand outwardly directed tooth 125 by which it may engage the inner rack 103 of its companion rack lever (Fig. 5) and a right hand inwardly directed tooth 126 (Fig. 2) by which it may 45 engage the outer rack of the rack lever in the next order to the right. As explained in Patent No. 1,316,523, page 9, a pawl 128 is pivoted on the dog lever and is provided with an outwardly extending tail 130. A 50 transverse rock bar 131 pivoted in the main frame has fixed thereto a series of L-shaped arms 132 (Figs. 2 and 5) which are adapted to depress the pawl tails 130 when said bar 131 is rocked forwardly, thereby disengaging 55 all of the pawls 128 from the aforesaid dog-carrying frame. The normal position of the parts is neutral (Fig. 2) with the pawls 128 in engagement with the dog-carrying frame and the oppositely projecting 60 dog teeth 125 and 126 out of engagement with the rack of either the lever to the right or to the left of the dog. This position permits the setting of the rack levers, as above described. As soon as the rack levers have 65 been so set, the initial movement of the

power shaft 100 causes the bar 131 to be rocked forwardly (see Figs. 27, 28 and 29^a of my Patent 1,316,523), thereby releasing the pawls 128 (see also Figs. 25, 26, 30, 22 and 23 of my said Patent 1,316,523 and its page 9, 70 lines 55-71 et seq.), and permitting the spring actuating dogs to engage the inner racks 103 of their companion rack levers. Immediately thereafter, the bar 120 is rocked rearwardly so as to release the pawls 116 75 from the ratchets 107 of the rack levers. This leaves the multiplying levers free for vertical vibration, the companion rack lever and dog lever of each lever assembly being 80 locked together and working as one lever. In operation, each multiplying lever assembly is alternately pulled down by the springs 112 and 113 and elevated by the cams 111. The arms 114 which drive the adding mechanism rising as the rear ends of the levers 85 are let down by the cams. As the said multiplying levers are so vibrated the tooth 105 of each one descends to the stop bar 106 and rises therefrom, each lever having a particular additive degree of stroke for which it 90 has been set. Thus, while the cams 111 all have the same throw and allow the multiplying levers to start downwardly from the same height, each lever has its own additive throw determined by the set distance of the tooth 105 of the rack lever from the stop bar 106. The stopping position of the multiplying lever at the top limit of the cam throw represents the stopping of the column 95 actuator at its low point, according to the key which was depressed to set it. 100

Key set and automatic control connecting device (see especially Figs. 2, 3, 4 and 5)

This device connects and disconnects the adding mechanism and the multiplying mechanism, and is operated to convert the key driven machine to a key set machine, and vice versa. In the particular construction illustrated, it connects the column actuators 8 with the lateral lugs 115 of the multiplying levers. Each column actuator 8 is provided with a link 139 pivoted thereto at 140, pressed rearwardly by a spring 141 and formed with a jaw 142 on its rear side. In the normal position of the rack levers 102, with their rear stop arms 105 depressed against the stop bar 106 and their forward arms 114 elevated (Fig. 2), the lugs 115 will be exactly opposite to the jaws 142, and it is at this time that the jaws are swung rearwardly to engage the lugs. Each link 139 has fixed thereon a lateral pin 143, the rear side of which is engaged by one of a series of arms 144 fixed on a transverse rock bar or shaft 145, which is pulled to turn forwardly by a spring (see Fig. 40 of Patent No. 1,316,523). When this shaft is rocked forwardly the arms 144 swing backwardly, 115 releasing the pins and permitting the 120 125 130 135 140 145 150 155 160 165 170 175 180 185 190 195 200

springs 141 to force the jaws of the links 139 into engagement with the lever arm lugs 115, whereby each upward and downward movement of the multiplying levers 102, 108 5 causes a movement for the same distance of the column actuators 8 and a corresponding accumulation on the adding machine. However, a multiplying lever will have no vertical movement unless a key of the adding 10 machine, and in the order to which the lever belongs, has been depressed subsequent to the connection of the lever and column actuator. This is more fully described in my aforesaid Patent 1,316,523 at its page 8, line 15 105 to page 9, line 25 et seq. and its page 10, lines 19-40, and shown in its Figs. 22 to 30.

Pivoted at 147 on the main frame and formed with cam slots 148 and 149 is an angle lever 146. The cam slot 148 engages a 20 roller 150, provided on a forward arm 151 of a lever which is pivoted on the journal of the rock shaft 145 (shown and described in my aforesaid Patent 1,316,523 in its Figs. 15 and 6 and its page 11, lines 28-36), the 25 said lever having a rear arm 152 terminating in a lip 153, which engages the top of the rear part of the rectangular portion of the rock shaft. The rearward arm of the angle lever is connected by a link 154 with 30 a setting segment 155 pivoted on a cross rod 156 of the frame. (Fig. 3, and see also my aforesaid Patent 1,316,523 in its Fig. 15.) Said segment is provided with a projection 134 extending through a slot in the casing 35 and affording a handle by which the segment may be set at will (Fig. 15). On the exterior of the casing by the slot may be marked a rear, a front, and an intermediate position for the setting segment. These 40 marks may conveniently be respectively "Add" "Mul" and "Div". When the handle is at "Add", the rear part of the slot 148 has thrown the arm 151 upwardly and the lip 153 has rocked the shaft 145 rearwardly, 45 with the result that the arms 144 move forwardly against the pins 143, thereby holding the links 139 away from the lugs 115. In such position, the adding mechanism is disconnected from the multiplying levers 50 and becomes freely key-driven, to be employed at will for rapid addition and subtraction (subtraction being of course performed by complementary addition, employing the codigital markings on the adding 55 keys, as in the well known Duplex comptometer machines of, for instance, the aforesaid Felt Patent 762,520). When the handle is at "Mul", the middle part of the slot 148 has caused the arms 144 to swing rearwardly and to permit the jaws 142 to grasp the lugs 115, in which position the machine 60 becomes key set. Any setting of the adding keys is maintained by the pawls 116 and thereafter by the dogs 109, as already explained. This is shown and described in

my aforesaid Patent 1,316,523 in its page 11, lines 50-67 and page 9, lines 12-68 et seq. and page 10, lines 19-40 and in its Figs. 22 to 30 and its Figs. 15 and 6.

It is preferable that the column actuator return upwardly by the power of its own spring 10, and independently of the multiplying lever. For this purpose, all of the links 139 are disengaged from the multiplying lever arms 114 at the bottom of the stroke. This mechanism is described in detail on page 11 of Patent No. 1,316,523 and need not be set forth in detail in the present application. The said disengaging mechanism is operated to permit the links 139 to re-engage with the multiplying levers to permit further actuation of the segment levers by the multiplying mechanism. The said links 139 are also disengaged from the multiplying levers to prevent accumulation for a cipher in the multiplier as will be hereinafter explained.

The actuating crank mechanism (see especially Figs. 3, 5, 6, 7, 8, 9 and 14)

The multiplying mechanism is locked against operation until the handle 134 has been set at multiplication or division; until the key has been depressed on the adding key board; until a control device for the multiplying mechanism has been set; and until a release key 171 has been depressed. The cancelling or zeroizing handle 53 must be in its normal forward position but the details of these locking means are left for later explanation.

The crank or power shaft of the multiplying mechanism, which in accordance with the present invention may be either power driven or driven by hand, is shown at 172 and extends transversely across near the front of the machine, being mounted in suitable bearings in the frame. From this shaft which is, in the manner illustrated, rotated toward the rear of the machine, or in a counter clockwise direction as viewed in Fig. 3, an oscillatory movement is transmitted to the main operating shaft 100. The rock shaft 100 supplies the power for most of the operations of the multiplying mechanism. A crank wheel 165 (Fig. 3) is mounted on the left end of the power shaft 172 and a wrist pin on said wheel is connected with a pitman 174, pivoted at 175 on a swinging arm 176. A toothed rack 177 meshing with the top of a toothed segment 178 on the rock shaft 100 is also pivoted at 179 to the said swinging arm. The rack 177 is guided by a frame 180 provided with rollers 181 which hold the rack in engagement with the segment. The said swinging arm 176 (Fig. 3 and also my aforesaid Patent 1,316,523 in its Figs. 18 and 19) is pivoted on the main frame at 183 and has attached thereto a parallel plate 184, providing the

arm with a bifurcated upper end. In this bifurcation formed by arm 176 and plate 184 the pitman 174 is pivoted. The pivot 179 of rack 177 is vertically adjustable on the swinging arm by having its pivot mounted in slots 185 where it is clamped by a nut 186. By this means, the angle of rocking of the shaft 100 may be accurately determined.

When the power shaft has started to turn rearwardly at the beginning of an example, its first effect is to turn the main cam shaft 100 forwardly for a short arc from the position shown in Fig. 5. This causes certain movements before the rearward rock of the cam shaft begins and the rear ends of the multiplying levers begin to descend. First the rock shaft 131 is turned forwardly to release the dogs 109 and allow them to spring upwardly. This is accomplished (as more fully shown and described in my aforesaid Patent 1,316,523 at its page 12, line 106 to page 13, line 33 and in its Figs. 27, 28, 25, 26, 29a and 22) by a toggle 208 through which the shaft is rocked and by the breaking of which the shaft is returned to normal position. A pin 192 (Fig. 3) projects from an arm 193 (Fig. 3 and also more fully shown in my aforesaid Patent 1,316,523 in its Figs. 18, 19 and 6) fixed on the main cam shaft 100 at the left of the machine. On the forward rocking of the shaft 100 said pin engages the hook 194 of a link 195 and pulls the link forwardly. The said link 195 is pivoted at 196 to the lower arm 197 of an angle lever having an upper arm 198 and mounted on the frame by a pivot 199. The link 195 is also connected with said arm 197 by a spring 200 tending to pull the link upwardly, such action being limited by a stop 201 (Fig. 3 and also in my aforesaid Patent 1,316,523 in its Figs. 27 and 28 and at its page 12, line 128 to page 13, line 17) on the link which engages the front of the arm 197. The rearward movement of the arm 197 is limited by a stop pin 202 on the frame (Fig. 3) and after the arm 197 has been pulled forwardly by the action of the link 195 from the position shown in Fig. 3 said arm 197 bears against a pin 203 on an arm 204 of the rock shaft 120, (Fig. 4 and also in my said Patent 1,316,523 in its Figs. 25 to 30 and 22 and at its page 9, line 31 et seq.) the said arm 204 being pulled rearwardly by a spring 205 (Fig. 4). The forward movement of the link 195 rocks the upper arm 198 rearwardly causing it to press on a short lateral lug of an arm 207 (Fig. 3 and also in my said Patent 1,316,523 in its Figs. 27 and 28 and its page 13, line 12 et seq.) mounted on the said pivot 199, thereby rocking the arm 207 rearwardly. The arm 207 is connected by a toggle 208 with an arm 209 fixed on the rock shaft 131, whereby the latter is rocked forwardly to trip the dog pawls 128 (Fig. 5).

On breaking of the toggle in the manner fully set forth on page 13 of Patent No. 1,316,523, the rock shaft 131 is allowed to rock backwardly thereby releasing the dog pawls 128. This tripping and releasing of pawls 128 is more fully shown in Figs. 25, 26, 30 and 22 of my said Patent 1,316,523. Pivotally mounted on the rock shaft and controlled by a spring is a two-armed latch 215. As the arm 198 moves rearwardly, the latch 215 drops over the upper end of the arm 198 and holds it in rearward position, while the pin 192 rocks rearwardly. The forward swinging of the arm 197 under the pull of the link 195 has changed the angle between it and the link 195 and separated the stop 201 from the arm 197; as the pin 192 moves back from over the hook 194, the spring 200 pulls the link up out of the path of the pin. 217 is an arm on the transfer shaft 218 which bears against the rear arm of the latch 215, and when this shaft rocks forwardly it throws up the latch allowing the parts to return to normal position (excepting that the arm 197 will be against the pin 202).

Second, the rock shaft 120 (Fig. 5) is turned rearwardly to release the set pawls 116. This is accomplished (Fig. 3) by the lever arm 197 shifted by hook-link 195 engaged by pin 192 on plate 193 attached to shaft 100. Immediately after the two pairs of the multiplying levers have been locked together by the dogs the lower arm 197 of the angle lever turns forwardly and actuates the pin 203 on the arm 204 of the shaft 120. This overcomes the tension of the shaft returning spring 205 and rocks the shaft rearwardly enough to engage the tails of the pawls 116 and release the pawls (Fig. 5).

Multiple control mechanism (see especially Figs. 2, 3, 4 and 5)

This mechanism automatically determines the number of additive strokes which shall be made for each digit of the multiplier, which may be from 1 to 9. It comprises several orders (according to the capacity of the machine) of oscillating parts including numeral wheel indicators 219 (Fig. 2) working by eleven stepped positions. The first nine steps between these positions, that is to say, from 9 to 0, are additive; the next step from zero to blank or normal is additive in preparation for the automatic operation of the next lower order of control mechanism. Each indicator wheel has its periphery divided into eleven spaces showing in order, as it rotates step by step forwardly, 9, 8, 7, 6, 5, 4, 3, 2, 1, 0 and a blank space. The principle of operation is to set each of the several orders of control mechanism which are desired to operate, back a certain number of these steps, according to the digits of the multiplier. Thus, if the

multiplier be 123 that indicator wheel 219 which is in line with the units order of the multiplicand is set to one (to represent the hundreds order of the multiplier), the next 5 lower wheel is set to 2 and the next lower wheel is set to 3. Then, after being so set, the orders of control mechanism one after the other beginning with the highest, are caused by the power mechanism to return 10 step by step to their normal positions, and an additive stroke of the multiplier levers being made for each step of such return, with the exception of the step from zero to blank. Such setting and return of the control mechanisms are regulated primarily by eleven-tooth ratchets and suitable pawls. The indicator wheels 219 (Fig. 2) are mounted to turn on a cross rod 220 held in the frame, and they are covered by a removable 20 plate 221 provided with an aperture 222 for each wheel, said aperture being so arranged that when the wheel is in normal position the blank space shows through the aperture and when the wheel is turned back 25 to multiply for any digit such a digit will show through the aperture.

Each order of the control mechanism (with exceptions as to the highest and lowest orders hereinafter noted) is further provided with the following parts: a series of 30 setting keys 223 marked from 9 to 0, each having in setting function a multiplier digit value corresponding with its marking, each key being mounted to slide radially inwardly and outwardly in the plate 221 and spring 35 pressed outwardly. When the key is depressed, it releases the control mechanism of its order and acts as a stop (page 14 of Patent No. 1,316,523) to arrest the same in 40 position to cause thereafter as many multiplying strokes as there are units in the marking of the key. Inasmuch as the multiple control mechanism is not shown in detail in the drawings of the present application 45 reference is made to pages 14 and 15, and more particularly Figs. 31 to 39 inclusive of Patent No. 1,316,523 for a detailed description of the parts of the multiple control mechanism. The details of these parts, 50 however, form no part of the present invention and, for the sake of simplicity, it will be thought sufficient to give a general outline of the operation of the multiple control mechanism.

Assuming that the setting keys are set 55 to indicate the multiplier "123" and the adding keys have been previously set to indicate the multiplicand 456, the machine 60 would now be ready for operation if it were not for the locking of certain parts to guard against manipulation, the various locks being controlled by the locking key 171. The description of said locks can 65 best be understood later, and the descrip-

tion of the operation of the multiple control mechanism is continued under the assumption that the locking key 171 has been depressed to release the locks. As the power shaft of the machine is actuated, the main cam shaft is caused to rock first forward and then backward and forward as above described. 70

When, in the above operation, the control arrives at "0", a number of additions of 75 the multiplicand corresponding with the digit of the multiplier have been made, and no more such additions are to be made of the multiplicand in its present setting on the adding mechanism, but the multiplicand is to be trans-set one place to the right before its repetition by the next lower stroke control begins. Such shifting or trans-setting is performed by the trans-setting mechanism herein described. But it is first necessary that the mechanism of the higher control refrain from causing any addition during the remaining step from zero to normal. This is insured by the cipher control mechanism, the operation of which is more or less 80 coincident with the operation of the trans-setting mechanism. 85

The multiple stroke controls are not actuated one by another in the preferred form of the machine. A higher control will bring 90 parts to such position that the operation of a lower control may be caused to begin, but the actual operation of the control is from the power mechanism, separately by 95 each control. The number of multiple controls may therefore be readily increased to 100 enlarge the capacity of the machine.

Cipher control mechanism (see especially Figs. 2, 3, 4 and 5)

105

For a complete description of the cipher control mechanism, reference is made to pages 16 and 17 and especially Figs. 40 and 41 of Patent No. 1,316,523. The cipher control mechanism prevents accumulation for 110 any factor-cipher and is controlled by the corresponding factor-setting device. The cipher control mechanism operates whenever the active (highest) control reaches the zero position, because the next higher control is then at the normal position either 115 because it was not set or because it has finished its cycle. This operation also occurs when the next lower control becomes active 120 at the zero position, having been originally so set. If the original setting of the multiplier were 3000003 and the multiplicand 999, the highest control would cause 999 to be 125 repeated three times at the left, then the 999 would be repeatedly trans-set to the right six times without an additive stroke, and then 999 would be repeated three times at the right, giving the product of 2,997,002,997. It will be noted from the foregoing that 130

controls are always to be set at zero (and not left unset) to represent all intermediate ciphers in the multiplier. Ciphers terminating the multiplier, need not be set up. 5 Ciphers at the left of the multiplier, as in multiplying by .0024, must not be set up, because the setting of the adding keys has begun an accumulation of 24 which the cipher control does not prevent.

10 *The column trans-setting mechanism, (see especially Figs. 2, 3, 4 and 5)*

For a complete description of this mechanism reference is made to pages 17 and 18 15 and particularly Figs. 42 to 54 inclusive of Patent No. 1,316,523. The term "trans-setting" is herein employed to signify that the setting that has been given the mechanism in one ordinal place in the machine is 20 thereafter derived, that is, determined by and transferred, from that ordinal place and given over to mechanism in another ordinal place, to delimit similarly the action 25 of the latter. In the preferred embodiment of the invention, such trans-setting means is independent of the primary setting means and is also automatically operated without 30 manual intervention. Whenever the multiple control mechanism of the highest order 35 which has been set has finished all of its multiplying strokes, its indicator wheel will show blank and all of the multiplying levers will be at the bottom of their strokes against the stop bar 106. The dogs 109 will or may 40 be at various heights above the stop bar, according to the various digits of the multiplicand and the corresponding setting of the dog levers 108. At this time all of the 45 dogs will be situated radially within arc bars 358 (Figs. 2 and 5) which are pivoted at 359 to the lower ends of equalizing parallel arms 360 pivoted on cross rods 361 held in the frame. There is an arc bar for each 50 dog and it is formed on its inner face with ten notches 362 to correspond with the possible ten positions of any dog. The arc of the inner notched face of the bar is concentric with the lever pivot 101. Each bar 55 is formed with a short downwardly and rearwardly extending slot 363 in which works a flanged roll 364 (Fig. 5). Each roll is pivoted at 365 to the left side of an arm 366 all of which arms are fixed on the transverse 60 trans-setting and neutralizing rock shaft 218 mounted in the frame. When the parts are in the last described position, the shaft 218 is rocked forwardly to cause all of the arc bars to engage their respective dogs 109, 65 and force the latter inwardly against the tensions of their springs until the dogs are each released from the inner racks 103 of their companion rack levers 102, and past the neutral point, and engage by their outer right hand teeth 126 the outer racks 104 of

the rack levers in the next lower orders to the right of the respective dogs 109; whereupon the dog pawls 128 engage the teeth of the respective dogs 109 as set for in (and shown in Figs. 22 to 29 of) Patent No. 1,316,523. Thus each rack lever which was originally set is for the time being freed from its own dog lever 108 and is locked and moved for one upward stroke with and by the next higher dog lever. The highest 75 (extreme left hand) rack lever has completed its multiplying functions and is left resting on the stop bar, locked at the neutral or inoperative position. The main cam shaft 80 now elevates all of the dog levers, each carrying with it the right hand rack lever with the same additive setting which the rack lever formerly had on its own dog lever. While the dog levers are returning to their highest point the first accumulation of the new setting occurs, and after they have reached the highest point, they are all in line across the machine; and at the same time the shaft 131 is rocked to depress the tails of the dog pawls 128. This releases 85 each dog and they spring outwardly into engagement with the inner racks 103 of their own rack levers, the latter having at the instant the new settings just described, whereby said new setting is preserved during the 90 next cycle of the multiple control mechanism. Thus each multiplying lever has now the additive setting which the lever next to the left of it formerly had, and each digit 95 of the entire multiplicand is trans-set to an order one place lower than it formerly had, in which new orders it is now repeated as many times as there are units in the second (from the left) figure of the multiplier. It 100 will be understood that such trans-setting drops out of operation the higher column actuator 8 which was formerly driven, and brings into operation a new column actuator to the right, each active column actuator now 105 adding the same amount as the next higher column actuator added in the first cycle of operation. Similar cycles of operation are repeated according to the denominations of the multiplier, until the latter is exhausted 110 and the indicator wheels of the multiple control mechanism all show blanks. 115 When the lowest newly set rack lever, having been inactive, is thus set by its arc bar 358 it is at the moment resting on the stop bar 106 in its lowest position. It gets 120 its proper setting because, although it is not raised, as in an original setting, the left hand dog lever is at the moment depressed just the proper distance to give to the right hand rack lever the same additive stroke as its own left hand rack lever has. It is now raised for one upward stroke by this left hand dog lever, its own dog lever 125 remaining in neutral position, whereby when the dog pawl 128 is tripped and the dog 130

springs upwardly, this rack will be locked to its own dog lever with the same proper additive throw (to and from the stop bar) as if it had been set up by the depression of a key as in its original setting.

The trans-setting rock shaft 218 is rocked forwardly as above described after the active control has reached the normal or last position. The lower arm 367 (Fig. 3 and also 10 in my said Patent 1,316,523 in its Figs. 6, 47 and 48) which is fixed on the left hand end of this rock shaft 218 is constantly pressed forwardly by a spring 368 (Fig. 4), the turning of the shaft, however, being 15 limited by a stop arm 369 which rests against the rear side of the stop bar 106. Engaging the front side of the arm 367 (Fig. 3) is a lever 371 which is pivoted on a bearing of the shaft 218 and is limited as to rearward 20 turning by the fixed stop pin 213. Pivoted at 372 on the arm 371 is an angle lever constituting a trans-setting link 373 and arm 374. A spring 376 acts to pull the link 373 rearwardly and the arm 374 downwardly. 25 The link 373 is formed with a hook 377 by which the link may be pulled downwardly by a pin 378 when the hook is caused to move upwardly under the pin. The pin is fixed on a plate 379 which turns loosely on 30 the bearing of the main shaft. At the outside of the plate 379 is a cam and hook plate 193 fixed on the main shaft so as to rock constantly therewith and formed with an internal cam (see Patent No. 1,316,523, 35 Fig. 18) and with a downwardly turned hook 381. The link 373 has fixed thereon a roller 382 which extends into the cam opening of the plate 193, the rear part of the cam being shaped to let the hook 377 40 swing upwardly under the pin 378 and the front part of the cam being adapted to draw the roll 382 toward the center and to remove the link hook forwardly from under said pin 378. The plate 379 is pressed so 45 as to elevate yieldingly the pin 378 by a spring 383 and such tendency is limited by a fixed pin 384 which arrests an arm of the plate. The arm 374 of the link extends forwardly and upwardly and is formed with a 50 front inwardly turned lip 385 and a rear lip 386. The arm 387 attached to the rock shaft 281 is normally under the forward lip 385 to prevent the hook 377 from swinging rearwardly even if the cam of the plate 55 379 would allow it to do so. This arm 387 is turned rearwardly to release the link arm after the active control has reached normal position by the pushing stop 280 (Fig. 2). The construction is such that after a control 60 has accomplished its additive steps the latch 273 has been depressed and the pushing stop 280 has rocked the shaft 286 rearwardly. The link arm 374 is thereby released by the arm 387 and is pulled down by the 65 spring 376 (Fig. 3) so that the hook 377 moves rearwardly under the pin 378. At

this moment, the hook arm 193 rocks downwardly engaging the pin 378 and forcing it down on the trans-setting hook 377. Thereby the arm 371 is pulled down and the lip thereof caused to force back the lower 70 arm 367 of the trans-setting shaft 218, which forces the arc bars 358 (Fig. 5) and trans-setting dogs fully forward, as already described. During this movement, the cam arm 235 (Fig. 2) is rocked forwardly by 75 the movement of its segment 234 thereby lifting the pushing arm 280 until it is latched by the hook 278 in normal position.

Column trans-setting lock (see especially Figs. 2 and 3)

When the motor set control has reached the normal position, the example is finished and it is desirable to bring the whole machine to normal position. This operation includes that of bringing the dogs 109 to neutral position so that they do not rock any rack levers. This is accomplished by an operation quite similar to the trans-setting operation. Before this is performed, however, the trans-setting mechanism (or the primary actuating portion of it) is locked so that the dogs 109 will be forced only partly inwardly. When all of the multiple controls to the left have arrived at 85 normal and the extreme right hand control is still at zero, the V-pins 270 carried by the rack bars 268 are in the notches of the notched fingers 271 (Fig. 2). In this position, the trans-setting rock shaft 388 has 90 rocked backwardly because the notches of said fingers 271 are long enough to accommodate the V-pins in both the first and in the (further rearward) normal position. Therefore all of the V-pins have notches 95 beneath them and the fingers can rise and allow the shaft 388 to turn under the pull of its spring (see Fig. 55 of Patent No. 1,316,523). 391 is a latch (Fig. 3) fixed on the shaft 388 and adapted to be hooked under the rear lift 386 of the trans-setting link arm, though out of engagement therewith except at this time. The said rocking of the shaft now throws the latch 391 forwardly under the said lift and holds the trans-setting link 374 out of operation, so 100 that the trans-setting shaft cannot be moved thereby.

Neutralizing mechanism (see especially Figs. 2 and 3)

It is the object of this mechanism to restore parts of the machine, especially the multiplying levers, to normal positions leaving the said levers with their two parts unlocked by the dogs and separate just as they were when the above described multiplying operation was first begun. This is accomplished by a trans-setting shaft operating 125 mechanism, which, in this instance, is ar-

ranged at the right side of the machine. It operates to force the dogs inwardly, in a general way similarly to the trans-setting mechanism, already described, and which is arranged at the left side of the machine. The construction of the neutralizing mechanism is fully set forth on page 20 (Figs. 57 to 59 inclusive) of Patent No. 1,316,523 and is such that, when the last multiplying control reaches normal position, the shaft 415 is rocked backwardly to cause the arc bars 358 to force the dogs 109 inwardly to neutral position, without engaging either the inner or outer racks of the rack levers. The dogs are thus forced not fully inwardly but only to neutral position. While the neutralizing of the multiplying levers is thus being performed the trans-setting link 373 which would otherwise operate, is held out of action by the latch 391. After this, the power shaft makes its final turn of about a half a revolution, the locking key 171 springs up and the machine comes to rest with all of the parts in normal position and with the product or other result shown on the adding numeral wheels.

Re-setting and safety locking mechanism (see especially Figs. 2, 4, 5, 6, 7 and 8)

Most of this mechanism is connected with the said locking key 171, so that various locks are effected by the depression of the key, which remains depressed and reciprocally cannot itself be released until all of the mechanical movements necessary to the problem to be performed have been fulfilled, whereupon said key is automatically released. The key 171 operates to connect the power drive to actuate the machine, when the machine is set for operation by the power drive, and, when the key 171 is released the power drive is automatically disconnected, as will be explained hereinafter. The main power shaft 172 may be locked against rotation, whether driven manually or by power, by the main locking pawl 190 (Fig. 6) which is adapted to engage an abutment 189 mounted on said shaft. The said locking pawl 190 is pivoted on the cross rod 190^a and is pivotally connected at 422 to a link 421 (Figs. 6, 7, 8 and 14). The other end of said link 421 is pivotally connected to the upper end of a crank arm 421^a mounted on a shaft 421^b suitably journaled in the frame. The shaft 421^b carries a second crank arm 421^c to the upper end of which is pivotally connected the link 421^a (Fig. 8); the said link 421^a is pivoted at 423 to a lever 424, the latter being pivoted at 425 to the main frame. This lever is loosely connected by a pin 426 and slot 427 with another lever 428 which is pivotally mounted at 429 on the frame and has a lower arm 430 (Fig. 7) and an upper arm 431 on the inner face of which is fixed

a pin or roll 432. This roll is arranged in the cam slot 433 formed in the locking lever 434 which is pivoted to the main frame at 156, is pulled upwardly by a spring 435, and has fixed to its front end an arm 436 which extends through a vertical slot 437 in the casing (Fig. 8) and carries at its outer end the said locking key 171. (Fig. 5 and also in my said Patent 1,316,523 in its Figs. 63 and 61.) The construction, and the shape of the aforesaid cam slot 433, are such that if the key 171 be in its elevated position, which it occupies normally unless the example is being performed, and which is shown in Fig. 8, the lower arm 430, the lever 424, and the links 421^a and 421 will be forced forwardly, thereby locking the pawl 190 against the rear face of the projection 189 on the power shaft. Fig. 8 shows these parts 421^a and 421 in such forward position, and this is also clearly shown in Fig. 63 of my said Patent 1,316,523. If the locking key be pressed downwardly, the power mechanism is freed for operation by reason of the lifting of the pawl 190 by the said connections. 438 (Fig. 7) is a latch pivoted at 439 to the frame, having its rear end pressed down by a spring 440 so that the rear end of the latch rests on a pin 441 fixed on the slotted cam 54 of the cancelling mechanism. This latch is formed with a shoulder 442 and the arm 430 has an outwardly bent lip 443 adapted to engage with said shoulder when the pin 441 is depressed during the actuation of the cancelling handle 53. 444 (Fig. 7) is a horizontal shoulder or hook formed on the said arm 430 and adapted to engage beneath another pin 445 fixed on the said slotted cancelling cam 54. The arrangement is such that when the locking key is elevated, the cancelling handle may be turned and the cancelling or zeroizing of the adding machine performed, and if the adding keys have been erroneously set in connection with the multiplying levers, and the locking key not yet depressed, the machine may be cleared by the usual operation of the cancelling handle, with which cooperates the key set clearing device hereafter explained. But, as soon as such cancelling movement begins, the depression of the pin 441 allows the shoulder 442 to engage behind the lip 443, thereby locking the arms 430 and 431 and preventing the locking lever 434 (by reason of the shape of the slot 433) from being depressed until the cancelling mechanism is returned to normal position. When the locking key 171 is depressed, the shoulder 444 engages beneath the pin 445 and prevents the operation of the cancelling mechanism. Any interference of the multiplying mechanism with the cancelling mechanism, in respect of their actions on the column actuator, is thus prohibited.

The locking key 171 is also held from depression to release the power mechanism for operation whenever the setting-device handle 134 is set at "Add." 446 (Fig. 8) is a horizontal lever pivoted at 447 to the frame and having at its rear end an upturned stop 448 adapted to be elevated behind the pivot 423 so as to hold the levers 424 and 428 from turning, in which case the slot 433 will hold the locking lever from being depressed. Also, when the locking lever is depressed, the pivot 423 will be over the stop 448 and will prevent the rear end of the lever 446 from rising. Formed on the front end of the lever 446 is a lip 449 which is arranged to rest on the rear side of the rock shaft 450, (Fig. 7 and also in my said Patent 1,316,523 in its Fig. 63) the rear end of the lever 446 tending to fall by gravity. When the setting-device handle 134 is set at "Add", the links 139 (Figs. 2, 4 and 5) are disconnected and the multiplying arm 114 cannot be depressed. These arms 114 have mounted on them rolls 451 adapted on the depression of the arms to rock forwardly the cam arms 452 with which the rolls engage. These cam arms 452 are fixed on the shaft 450; consequently, the shaft 450 cannot be caused to rock rearwardly to release the lip 449 of the link 446, with the result that the stop 448 remains in position behind the pivot 423 and the lock lever 434 and key 171 cannot be depressed. The shaft 450 has fixed thereon an arm 450' (Fig. 3) formed with an outwardly turned lip 450" adapted to lock in front of the lug 146' on the angle lever 146 when the machine is set at "Mul." and the shaft 450 is rocked rearwardly by the rolls 451. This prevents restoring the machine to "Add" while a multiple stroke example is set thereon. The locking key cannot be depressed until at least one adding key has been set, because the upturn stop 448 does not release the pin 423 and the locking key lever until the shaft 450 has been rocked upwardly by a roll 451 of a multiplying lever. Also, the locking key cannot be depressed to release the power shaft until an indicator key 223 and a control mechanism has been set and when the key is depressed it causes the power mechanism to start the proper (highest) control into operation. 464 is a cam slot formed in the rear arm of the locking lever 434 (Fig. 5) in which engages a roll 465 mounted on the side of a middle lever 466 (also fully shown in Figs. 60, 61 and 63 in my said Patent 1,316,523) pivoted at 467 on the neutralizing trip shaft 415. The lever 466 is formed with right and left lateral lips 468 and 469 (also in Figs. 60, 61 and 63 of my said Patent 1,316,523). The arm 414 (Fig. 5) fixed on the rock shaft 415 has its front end engaging the underside of the right lip 468. 470 is an arm which may be a part of the arm 419, fixed on the rock shaft 388 and having its front end engaging under the front lip 469 of the before mentioned middle lever 466. The depending arms 416 and 419 attached respectively to said rock shafts are connected by the springs 417 and 390 with the said middle lever 466, whereby the ends of the two side levers are pressed against the under sides of the said rear and front lips. The left arm 470 has at its forward end a shoulder or notch 471 adapted to be engaged by a lateral lip 472 on the locking lever 434 (Fig. 5). At the right hand side of the arm 312 (Fig. 4) is fixed a pin 473 below the path of which is arranged a link 474 having a hook 475 adapted to engage the pin so that the link can be drawn rearwardly by the pin. 476 (Fig. 4) is a link pivoted to the forward end of an arm 477 fixed on the shaft 415 (Figs. 4 and 5). This link is formed at its bottom end with a slot 478 which embraces a pin 479 fixed on the side of the rear end of the link 474. The hook link 474 is pulled downwardly by a spring 480 connecting it with the lower end of an arm 481 fixed on the rock shaft 298. The turning of the rock shaft 415 upwardly is adapted through the link 476 to raise the hook 475 into the path of the pin 473. This pin is oscillated by the main cam shaft as described in Patent No. 1,316,523, page 22. The said rock shaft 298 carries the stop arms 297 (Fig. 2) and has attached thereto the depending arm 482 which is pulled forwardly by the spring 483, the latter being connected with the said arm 481 (Fig. 4) and also has fixed thereon an upwardly extending arm 484 (Fig. 5) formed with an outwardly extending lip 485 embraced in a slot 486 of the locking lever 434. This slot has a shoulder 487 above which the lip 485 may engage, when the locking lever 434 is depressed to lock the same in such position. When the locking lever is otherwise free to be depressed and its key 171 is pressed downwardly the aforesaid spring 483 causes the lip 485 to engage above the said shoulder. This movement removes the arms 297 from their locking positions against the pawl cutout levers 255 (Fig. 2) permitting operation of the machine as explained in Patent No. 1,316,523, pp. 14, 15 and 22. 488 is a pin fixed on the side of the notched cipher control finger 291, one such pin for each pair of fingers. The front side of each pin is engaged by an arm 482, there being for each pin one arm fixed on the rock shaft 298. When the locking key 171 is elevated, the arms 482 force the pins 488 and pairs of notched fingers 291 rearwardly, thus relieving the V-pins 290 of friction to allow of the easy upward and backward movement of the internal tooth sectors 287 in the setting of the controls by the keys 130

223. When the controls have been set, and the locking key is depressed and the lip 485 springs back above the shoulder 487 (Fig. 5), the arms 482 swing a little forwardly 5 and allow the V-pins 290 to bear against the front edges of the fingers 291, and to enter the notches thereon when the pins arrive in front of the notches.

Similarly, and for the same purpose, the 10 V-pins 270 of the externally toothed sectors 268 are relieved of the pressure of the lock-notched fingers 271 and 272 when the locking key is elevated. When the locking lever is held up under the pull of the spring 435 15 (Fig. 8) the inner forward part of the slot 464 (Fig. 5) causes the arm 466 to be depressed, the right and left lips of which depress the side arms 414 and 470 and rock the shafts 415 and 388 slightly forwardly, 20 which movement rocks the said notched fingers 271, 272 attached to the said shafts downwardly to clear their V-pins. If it be attempted to depress the locking lever without 25 setting a control by a key 223, the slot 464 will rock the arm 466 upwardly and this will rock the shafts 415 and 388 forwardly, by the pull of their springs. This lifts the arm 470 attached to the shaft 388 (Fig. 5) and springs the notch or shoulder 471 in 30 front of the lip 472 on the locking lever 434 and holds said lever and the key 171 from being depressed. But if any control be set at one or more its V-pin 270 will be no longer over a notch of the corresponding fingers 35 271, 272 but will keep its notched finger down, with the result that, when the locking lever is depressed, the slot 464 and arm 466 will no longer rock the shaft 388 and consequently the arm 470 and shoulder 471 will 40 not be elevated to arrest the lip 472 of the locking lever. In such case, the lips 468 and 469 will be carried by the arm 466 upwardly and away from the ends of the arms 414 and 470 and the springs 417 and 390 45 (Fig. 5) will be extended. The arm 470 being attached to the forward rock shaft 388 which carries the fingers 271 whose notches extend under the V-pins when they are at normal and also when they are at 50 zero, the setting of any control at zero will not hold down the fingers 271 or the arm 470, and consequently such a setting will not allow the locking key to be depressed, for such a setting would not be functional in 55 a multiplying operation or in any multiple stroke example.

While the neutralizing operation is being performed, the operation to automatically release the locking key and restore it and its connected parts to normal position is taking place. At the normal position of the last control, the fingers 272 are allowed to rise (see Patent No. 1,316,523, p. 20) and the arm 477 (Fig. 4) moves upwardly raising the link 474 against the pull of the

spring 480. This draws the hook 475 into the path of the pin 473 as the latter is rocking backwardly, and the pin 473 pulls the link 474 backwardly together with the arm 481 and rocks the shaft 298 forwardly. This 70 throws the lip 485 of the arm 484 on said shaft 298 (Fig. 5) forwardly from above the shoulder 487, with the result that the locking lever 434 is released and springs upwardly with its key 171 under the pull of the spring 435 (Fig. 8). The upward movement of the locking lever 434 is accompanied by a downward movement of the arm 477 (Fig. 4) which carries the slotted link, but such downward movement is permitted 75 by the slot 478. When the shaft 100 rocks forwardly to its final and normal position the pin 473 releases the hooked link 474, which is then pulled downwardly by its 80 spring 480 out of the path of the pin. 85

When the locking key is depressed, it throws into engagement with its corresponding ratchet (see Patent No. 1,316,523, p. 14) only the driving pawl 231 (Fig. 2) of the highest set order of the multiple control mechanism. Although each of the arms 297 is removed from its pawl cutout lever 255, only the arm 238 of said highest order of the multiple control mechanism springs upwardly. This is because in the lower 90 orders the arms 238 are held downwardly by their springs 242, while in the highest order the pin 244 (at normal position in the next higher order), holds back the arm 243 and rests the pin 246 on the top of the slot 247, 100 allowing the spring 248 to pull up the arm 238, when the arm 297 is so removed.

The following is a summary of the principal functions and effects of the locking key 171 and its lever 434: the locking key 105 is locked against depression until the key setting devices are moved from "Add" to "Mul." or "Div.", until an adding key is depressed, until a control is set, and during 110 cancelling, and during this time the power shaft is locked against rotation and, when the machine is set for the multiple-drive the power is disconnected. The depression of the locking key releases the power shaft, when the machine is set for operation by the 115 motor, applies the power to operate the machine, locks the locking device of the power shaft against being locked, locks the adding stop levers against depression, locks the key setting device against being returned to "Add" and locks the cancelling device. 120 When the locking key rises, the key setting device may be returned to "Add", thus disconnecting the adding machine from the multiplying mechanism, the motor drive is 125 disconnected from the machine, if the machine is set for drive by the motor, and the power shaft is locked, the cancelling device is released, the stop levers and the adding keys are released, the V-pins of the inter- 130

nally toothed sectors are relieved from pressure of the vertically notched fingers of the cipher control, and the V-pins of the externally toothed sectors are relieved of the pressure of the two sets of horizontally notched fingers compressed in the trans-setting locks and neutralizing mechanisms, with the result that all of the parts of the machine return to normal.

10 *Key set clearing device (see especially Figs. 2, 5 and 7)*

The function of this mechanism is to cooperate with the cancelling device of the adding mechanism so that, if the machine has been set by the handle 134 for multiplication and keys have been set on the adding keyboard (with or without a setting of the control keys 223) for a multiple stroke example and it is discovered that the setting is wrong, the adding mechanism may be cleared by the cancelling handle 53, without going through the cranking operation and the performance of an undesired example. After such a setting, certain of the rack levers are locked up on the pawls 116 (Fig. 5) and the corresponding column actuators (Fig. 2) are held down below normal position, with the result that these pawls 116 must be released to permit the zeroizing mechanism to clear the machine and to restore the accumulating mechanism to zero. 489 (Fig. 5) is a clearing lever pivoted at 59 to the frame and provided with a jaw 491 which embraces the cancelling cross bar 57. With respect to vertical position, this lever is controlled by the cross-bar. On the rear end of the lever is mounted a roll 492 which, when the cross bar is depressed by the roll on slotted cam 54 (Fig. 7), at the initial movement of the cancelling handle, swings downwardly in the cam slot 493 provided in an arm 494 loosely mounted on the automatic actuator release rock shaft 120, and having fixed thereon a lateral pin 495 arranged to engage the rear side of an arm 496 fixed on said rock shaft 120. The said cam slot is of such form that when the roll swings downwardly, the arms 496 and shaft are caused to rock rearwardly engaging the pins 121 with the pawls 116 to release them. When the pawls 116 are released, in the course of operation of the multiplying mechanism, the arm 496 swings away from the pin 495, without any movement of the arm 494 or lever 489.

The motor drive mechanism (see especially Figs. 1, 6, 7, 8, 9, 10, 13 and 14)

This mechanism effects electric-motor driven operation of the calculating machine in any multiple stroke operation effected by the movements of parts hereinabove described. The motor drive mechanism provides for connecting the power, preferably

of a continuously operating shaft, immediately and automatically to the various parts of the machine to perform the multiple stroke example whenever the locking key 171 is depressed. When the locking key 171 is released at the end of the multiple stroke example, in the manner described above, the motive power is immediately and automatically disconnected from the machine, although the power supply shaft may continue to rotate, if desired. Provision is further made whereby the machine may be instantly converted from operation by power to operation by the ordinary hand crank 173 and vice versa. In accordance with the invention, whenever both factors of the multiple stroke example have been set on the keys 4 and 223, the machine may be driven by power to perform the calculating function, by the mere depression of the locking key 171 and the power is automatically disconnected from the machine as soon as the key 171 rises at the end of such calculating operation, it being unnecessary to start and stop the motor in any operation of applying power to or disconnecting it from the moving parts of the machine. This construction provides reserve power which is at all times instantly available for operating the machine to perform any multiple stroke example and avoids any necessity for operating switches or other parts for controlling the operation of a motor either at the beginning or at the end of the multiple stroke calculating operation.

The power for operating the machine, when the latter is power driven, may be primarily derived from an electric motor 701 (Fig. 1) on the armature 702 on which is fixed a suitable worm 703. The worm 703 meshes with and drives a worm gear 704, the latter rotating on a horizontal axis 705 and having fixed thereto a bevel gear 706 which meshes with and drives the bevel pinion 707. The bevel pinion 707 is fixed on a vertical shaft 708 and the latter is provided, at its upper end, with a jaw clutch member 709 adapted to co-operate with a companion jaw clutch member 710 (Fig. 9) of a vertical stub shaft 711 which rotates in a bearing 712 mounted within the enclosing walls of the calculating machine. As shown in Figs. 1 and 9, the jaw clutch member 710 of the shaft 711 has its clutch faces located within a socket 713 provided in the bottom plate of the calculating machine, but without such clutch faces extending beneath the lower face of said bottom plate. With this construction, the entire calculating machine may be instantly disconnected from the motor by simply lifting it off the frame in which the motor is supported, and removed to any flat surface on which the machine will remain supported in stationary position, whenever it is desired to disconnect the

machine entirely from the motor drive and remove it to some other place for operation entirely by the hand drive.

Assuming that the clutch member 710 is connected with the clutch member 709 for driving the calculating machine by the power of the motor 701, the shaft 709 will drive the stub shaft 711 continuously in the direction indicated by the arrow. At its upper end the shaft 711 is provided with a bevel pinion 714 which moves in unison therewith and meshes with a bevel gear 715 fixed on the spur gear 716 and adapted to drive the same. The spur gear 716 is mounted on a rod 717 supported by the main frame of the machine and meshes with and drives a spur gear 718, the latter constituting the constantly driven member of a clutch construction which will be presently described. Whenever the motor 701 is running, and the clutch member 710 is connected with the clutch member 709, the gear train constituted of the shaft 711, pinion 714, gear 715, gear 716 and gear 718 is operating continuously, whether the calculating mechanism of the machine be operating or not, and said gear train may be considered as a source of continuously available power from which power is transmitted from the gear 718 to the various instrumentalities of the calculating machine whenever the key 171 is depressed to unlock such parts for operation.

As shown in Fig. 10, the driving gear 718 is mounted to revolve freely on the hub 719 of a driven gear member 720 and said gear 718 has fixed to its inner face a ring 721 provided with a plurality of internal clutch faces 722. Between every pair of adjacent clutch faces 722 the ring 721 is formed with inwardly extending projections 723 the internal faces 724 of which are curved concentrically with the axis of rotation of the gears 718 and 720, permitting the gear 718 and its ring 721 to revolve freely relatively to the gear 720 and a projecting ring 725 carried by said gear 720, whenever the power is disconnected from the various instrumentalities of the calculating machine. Within the gear member 720 and the ring 725 is a socket 726 which extends parallel with the axis of rotation of both gears 718 and 720. Rotatably mounted in the aforesaid socket 726 is a clutch pin 727 the outer face 728 of which is concentric with the axis of the socket, but having its end adjacent to the gear 718 extended within the rings 721 and cut away to provide a face 729 concentric with the axis of rotation of the gear 718 and ring 721. This construction permits the projections 723 to clear the clutch pin 727 when the gear 718 and rings 721 are rotating, but when the gear member 720 is stationary.

65 The gear member 720 is provided with an

external spur gear 730 (integral with the rest of said flanged gear member 720) which meshes with a transmitting pinion 731, whenever the machine is set for operation by the power drive, as hereinafter explained. 70 The transmitting pinion 731 is in mesh with and drives a pinion 732 fixed on the main power shaft 172. The clutching of the gear member 720 to the continuously rotating gear 718 to drive the main power shaft 172 through the gears 731 and 732 is effected by the depression of the locking key 171, by means of the following instrumentalities: at its inner end, the before mentioned clutch pin 727 is provided with an operating pinion 733 in mesh with an internally toothed sector 734 carried by the clutch operating ring 735. The clutch operating ring 735 is loosely mounted on the hub of the gear member 720 and is provided at its periphery with a plurality of stops or abutments 736. A slot 737 (Fig. 6) is provided in the gear member 720 on that side next to the clutch operating ring 735. Within said slot 737 is a spring 738 one end of which bears against one end of the slot and the other end of which bears against a lug 739 carried by the clutch operating ring 735 and projecting into the slot 737. As shown in Fig. 6, the slot 737 is curvilinear in form and extends concentrically with the axis of rotation of the gear member 720 and the clutch operating ring 735, to permit a relative rotation between said gear member 720 and clutch operating ring 735, at the time 90 of the clutching and unclutching operations, as will be presently explained.

Normally, i. e., whenever the gear member 720 is disconnected from the constantly running gear 718, the spring 738 is held under compression by the lug 739 of the clutch operating ring 735 and the ring 735 is held stationary by the engagement of the clutch locking pawl 740 with one of the abutments or stops 736. The clutch locking pawl 740 is loosely mounted on the shaft 190^a of the main locking pawl 190 and is provided, with a toothed sector 741 (Fig. 8) in mesh with a pinion 742. When the machine is set for operation by the power drive, the pinion 742 110 is also in mesh with a toothed sector 743 provided on the main locking pawl 190.

With the above described construction, whenever the main locking pawl 190 is lifted by the depression of the locking key 171 through connections (421, 421^a, 421^d, 424, 431, 436, Figs. 6, 8 and 14) hereinbefore described, the pinion 742 is rotated by the sector 743 with the result that the sector 741 of the clutch locking pawl 740 is also rotated to lift said clutch locking pawl from engagement with an abutment 736 of the clutch operating ring 735. This operation frees the spring 738 which, as before mentioned, is normally under compression, with 130

the result that said spring effects a slight rotation of the ring 735 relatively to the gear member 720. As said ring 735 so rotates, the sector 734 will impart rotation to the pinion 733 sufficiently to turn the clutch pin 727, so that the edge 727^a formed at the junction between the faces 728 and 729 will bite into one of the clutch faces 722 of the constantly rotating gear 718. This results in a clutching of the gear member 720 to the gear 718, so that the main power shaft 172 will be driven by the gears 730, 731 and 732.

At the completion of the calculating operation, the locking key 171 rises, as already described, and the main locking pawl 190 is permitted to drop into position to engage the abutment 189 to lock the main shaft 172 against rotation. At this time the downward movement of the main locking pawl 190 will turn the pinion 742 to lower the clutch locking pawl 740. As soon as the clutch locking pawl 740 is positioned so as to lie in the path of one of the abutments 736 it will engage an abutment and stop the ring 735 from rotating. At this moment, however, the gear member 720 is being rotated by the gear 718, but the stopping of the ring 735 will cause the pinion 733 to be rotated on the segment 734 sufficiently to turn the clutch pin 727 to disengage its edge 727^a from a clutch face 722 and to restore the clutch pin to the position shown in Fig. 9, in which the gear 718 is disconnected from the gear member 720 and may rotate freely relatively to said last mentioned gear member. The slight movement of the gear 720 after the ring 735 is stopped by the pawl 740 is sufficient to compress the spring 738 against the lug 739 enough to give the initial movement to the ring 735, when the pawl 740 is released for another calculating operation. A pawl 757 is provided to prevent reverse rotation of the gear 720 which is provided with a three toothed ratchet 758 with which said pawl engages to hold said gear and other members of the train in normal position against said spring compression.

The invention provides means for optionally converting the machine from the power drive to a hand drive and vice versa. As shown in Figs. 6, 9, 10 and 13, the transmitting pinion 731 and the small pinion 742 are both journaled in a frame 744 (Fig. 14) which is slidably mounted on transverse rods 745 fixed on the main frame. At its rear end the frame 744 is provided with a rack 746 in mesh with a gear segment 747 formed at one end of the shifting lever 748. The shifting lever 748 is pivoted at 749 in the main frame and is provided at its opposite end with a gear segment 750 in mesh with a pinion 751 carried by a vertical shaft 752. At its upper end the vertical shaft 752 is

provided with an operating handle 753 mounted to swing under a hood 754 to and from a position H in which the machine is set for operation by hand and a position M in which the machine is set for operation by the motor drive. As hereinbefore stated, the gear 732 is fixed on the shaft 172. Adjacent to the gear 732 and loosely mounted on the shaft 172 is a gear 755 adapted to be operated by the crank handle 173 which is also loosely journaled with respect to the shaft 172. When the parts are in the position shown in Fig. 14 the frame 744 has been shifted so that the transmitting pinion 731 meshes only with the gear 732 and at the same time the small pinion 742 (Fig. 6) is positioned so as to mesh with the toothed segments 741 (Fig. 8) and 743 (Fig. 6) of both the clutch pawl 740 (Fig. 6) and the main stop pawl 190 (Fig. 6), with the result that the operation of the main stop pawl 190 will release the pawl 740 to permit the motor drive of the machine in the manner hereinbefore described. When however, the setting handle 753 is shifted to the hand drive position "H", the frame 744 is moved toward the right of the machine from the position shown in Fig. 14 to connect the gear 732 only with the gear 755, (and to disconnect the gear 732 from gear 730) so that the handle 173 may rotate the gears 755 and 732 in unison and drive the shaft 172. At this time the small pinion 742 has been shifted out of mesh with the gear segment 743 and the main stop pawl 190, with the result that the clutch stop pawl 740 will not be affected by the operation of the main stop pawl 190. Consequently the motor drive is locked against operation whenever the machine is set for operation by the hand drive. As shown in Figs. 8 and 14, the frame 744 is provided with a toothed segment 756. This segment 756 is shifted into mesh with the gear 755 when the frame 744 has been shifted to the position shown in Fig. 14, for setting the parts for operation by the motor drive, and the toothed segment 756 locks the gears 755 and the handle 173 against operation, whenever the machine is set for operation by the motor.

Mounted on the frame 744 and slidably on said rods is a stop 759 (Fig. 6) adapted to co-operate with a stop member 760 formed on the back of the main locking pawl 190. The stop 759 prevents movement of the main locking pawl to unlock the machine in any intermediate position of the frame (while shifting from one form of drive to another) and also has the function of preventing the frame from being shifted whenever the locking pawl is in released position. The movement of the frame to any intermediate position will position the stop 759 behind the stop member 760 to block the rearward unlocking movement of said pawl; whenever

the pawl 190 is unlocked the member 760 will be shifted across the path of the stop 759 to block any shifting of the frame.

Operation

5 The operation of the mechanism of this machine is fully described at line 33 of page 24 to line 9 of page 28 of my aforesaid prior Patent 1,316,523, except as to the motor 10 drive mechanism and connections, whose operation is described in the present specification under the preceding caption "The motor drive mechanism."

15 The invention as hereinabove set forth is embodied in a particular form of construction but may be variously embodied within the scope of the claims hereinafter made.

I claim:

1. In a calculating machine, in combination: 20 accumulator mechanism; multiplying mechanism adapted to actuate the accumulator mechanism; a continuously operating power member; a driven member connectable with said multiplying mechanism; a 25 spring actuated clutch interposed between said members; and a locking device, releasable only upon setting of the multiplying mechanism for both factors of a multiple stroke problem, for permitting such clutch 30 to operate to connect the driven member with the driving member; substantially as specified.

2. In a calculating machine, in combination: 35 accumulator mechanism; multiplying mechanism adapted to actuate the accumulator mechanism; a continuously operating power member; a driven member connectable with said multiplying mechanism; a spring actuated clutch interposed between 40 said members; a locking device, releasable only upon setting of the multiplying mechanism for both factors of a multiple stroke problem, for permitting such clutch to operate to connect the driven member with the 45 driving member; and means for resetting said clutch for further clutch actuation and for restoring said locking device to its clutch locking relation, at the conclusion of the multiple stroke problem; substantially as 50 specified.

3. In a calculating machine, in combination: 55 accumulator mechanism; multiplying mechanism adapted to actuate the accumulator mechanism; a continuously operating power member; a driven member connectable with said multiplier mechanism; a locking device for said driven member releasable only upon setting of the multiplying mechanism for both factors of a multiple stroke 60 problem; a spring actuated clutch interposed between said members; and means controlled by the actuation of said locking device to inoperative position for releasing said clutch.

65 4. In a calculating machine, in combina-

tion: accumulator mechanism; multiplying mechanism adapted to actuate the accumulator mechanism; a continuously operating power member; a driven member connectable with said multiplying mechanism; a 70 locking device for said driven member releasable only upon setting of the multiplying mechanism for both factors of a multiple stroke problem; a clutch interposed between said members; and means controlled by the 75 actuation of said locking device to inoperative position for effecting the operation of said clutch.

5. In a multiple order key driven calculating machine, in combination: 80 accumulator mechanism including numeral wheels; denominational series of keys and multiple stroke mechanism each separately adapted to actuate orders of the accumulator mechanism; control mechanism for automatically 85 determining the number of strokes of the respective orders of said multiple stroke mechanism; an electric-motor-driven continuously-operating power device adapted to operate the said multiple stroke mechanism; means releasable for connecting said power device with said multiple stroke mechanism only when said multiple stroke mechanism is connected with the accumulator mechanism and the multiple control mechanism is set for effecting a selective number of strokes of the multiple stroke mechanism; and means for disconnecting said power device from the multiple stroke mechanism when the operation determined by such setting is completed.

6. In a key driven calculating machine, in combination: 95 multiple place calculating mechanism enclosed in a casing and operable for additive accumulation by actuation of individual keys; keys adapted to drive said mechanism; a driven member permanently arranged within said casing and connectable with said calculating mechanism to operate the same; a manual power device 100 connectable with said driven member; a continuously operable electric-motor driven power device permanently arranged within said casing relative to, and also connectable with, said driven member; an electric motor outside said casing and connectable with said continuously operable electric-motor driven power device to drive the same; and means permanently arranged within said casing and operable for effecting the concurrent 110 connection of only one of said power devices with said driven member and for holding the other power device in inoperative relation 115 with respect to said driven member.

7. In a key driven calculating machine, 120 in combination: calculating mechanism enclosed in a casing and operable for additive accumulation by actuation of individual keys; keys adapted to drive said mechanism; a driven member permanently arranged 125

- within said casing and connectable with said calculating mechanism to operate the same; an electric-motor driven power device permanently arranged within said casing relative to said driven member to drive the same; clutch means permanently arranged within said casing relative to said driven member and said power device and operable for connecting said electric-motor driven power device to and disconnecting it from said driven member; and an electric motor outside said casing and connectable with said electric-motor driven power device to drive the same.
15. 8. A calculating machine that automatically performs multiplication in which both factors are multiple place and completely predetermined and effects the entire operation with mechanism whose ordinal positions are permanent, said mechanism remaining and operating in fixed ordinal places in the machine, combined with an electric-motor driven power device connectable with said mechanism only on the setting of the machine for both factors of the problem, an electric-motor connectable with said power device, and means for disconnecting said power device from the aforesaid mechanism on the completion of the problem.
20. 9. In a calculating machine, the combination with ordinal accumulator mechanisms; ordinal prime actuators therefor, having an idle stroke for positioning them for a subsequent active stroke, and an active stroke for effecting the actual actuation of the accumulator mechanism; and keys for determining the degree of actuation by the respective actuators; of a driven means common to, and adapted for, driving the respective prime actuators during only the aforesaid idle strokes thereof and of spring means tensioned by said actuators on their idle strokes and adapted for driving the respective prime actuators during the active actuating strokes thereof by the spring tension stored in the springs by the movement of the actuators on the idle strokes of the actuators, when determined by said keys; and an electric-motor-drive including electric motor for driving said driven means.
25. 10. A multiple-order calculating-machine controlled by multiplicand and multiplier keyboards, combined with a common member for transferring power to all the orders of actuating mechanism and adapted to receive hand or other flexible power, and means for delivering an inflexible power to the said common member, said means being controlled by the said multiplier keys, to regulate the varying amount of inflexible power required to effect the varying number of actuations of the actuating mechanism in accordance with the predetermined setting of the multiplier keys.
30. 11. A multiple-order calculating-machine controlled by multiplicand and multiplier keyboards, combined with a common member for transferring power to all the orders of actuating mechanism and adapted to receive hand or other flexible power, and means for controlling and delivering the inflexible power of an electric motor to the said common member, said means in turn being controlled by the said multiplier keys, to regulate the varying amount of inflexible power required to effect the varying number of actuations of the actuating mechanism in accordance with the predetermined setting of the multiplier keys.
35. 12. A multiple-order calculating-machine controlled by multiplicand and multiplier keyboards, combined with a common member for transmitting power for the actuations, which member may be operated by hand or other flexible power to provide the variable amount of power required for the variable number of actuations, a positive drive motor to operate said common member, and means to control the delivery of the amount of power transmitted from said motor to said common member, said means being in turn controlled by the setting of the multiplier keys thus providing such predetermined amount of inflexible motor power as may be selectively set on the multiplier keys which determine the multiple actuation.
40. 13. A multiple-order calculating-machine controlled by multiplicand and multiplier keyboards, combined with a common member for transferring power to all the orders of actuating mechanism and adapted to receive hand or other flexible power, a motor for delivering an inflexible power to the said common member, and means controlled by the said multiplier keys, to regulate the varying amount of inflexible power required to effect the varying number of actuations of the actuating mechanism in accordance with the predetermined setting of the multiplier keys.
45. 14. In a power driven multiple-order calculating-machine controlled by multiplicand and multiplier keyboards, a positive drive motor to furnish the power for said calculating machine, and means controlled by said multiplier keys, and adapted in turn to control the varying increments of power delivered to the calculating mechanism by the said motor in accordance with the value of the multiplier keys set.
50. 15. In a power-driven calculating-machine two multiple order keyboards, one for setting the multiplicand and the other for setting the multiplier, combined with controlling devices for inflexible power to regulate such increments of the said power as may be required in driving the mechanism of the calculator, said power controlling de-

VICES in turn being controlled by the multiplier keyboard.

16. In a power-driven multiple-order calculating machine controlled by multiplicand and multiplier keyboards, an electric motor directly acting to operate the mechanism of said calculating machine, said multiplier keys also acting to control the varying increments of the power itself that is required 10 from the motor for the multiple actuations in each order.

In testimony whereof I have hereunto set my hand.

JOSEPH A. V. TURCK.
